UNITED STATES PATENT OFFICE

GONZALO ANCIRA, OF HOUSTON, TEXAS

SAFETY LOCK

Application filed July 11, 1927. Serial No. 204,788.

This invention relates to new and useful improvements in a safety lock.

One object of the invention is to provide a safety lock for preventing the opening of containers, secured by the lock, and for the detection of the violation of such containers, or unauthorized opening thereof.

With the above and other objects in view this invention has particular relation to certain novel features of construction, operation and arrangement of parts, an example of which is given in this specification and illustrated in the accompanying drawings, wherein:

15 Figure 1 shows an inside plan view of the lock, partly broken away.

Figure 2 shows a longitudinal sectional view thereof, taken on the line 2—2 of Figure 1, and

20 Figure 3 shows a fragmentary bottom plan view of a slightly modified form thereof.

Referring now more particularly to the drawings, wherein like numerals of reference designate similar parts in each of the figures 25 the numeral 1 designates one section of the lock as a whole and the numeral 2 designates the other section thereof as a whole. One of said sections may be attached to the body of a box, envelope, or other container, and the 30 other section may be attached to the cover or flap, of said box, or envelope and said sections then interlocked, to secure the container closed in such a manner that any attempt to gain access to the contents of the container 35 will be indicated by the lock.

The lock section 1 is preferably formed of sheet metal, of rectangular form, with its opposing edges bent around into parallel relation with and underlying the main body portion and forming the underlying flaps 3, 4.

40 The free edges of these flaps overlap and are spaced apart with the flap 4 underlying the flap 3. The margins of the section 1 have suitable teeth, or spurs 5 adapted to pierce the container wall and to be clinched on the inner side thereof to secure the section 1 to the container. At the junction of the flap 3 with the main body of the section there is an oblong slot 6, for a purpose presently to be described.

50 The section 2 of the lock is also preferably

formed of sheet metal, and has marginal teeth, or spurs, as 7, adapted to pierce the material of the container and to be clinched on the inner face thereof to secure said section 2 to the container. This section 2 may be of any 55 desired contour and has a tongue 8 reduced in width, with respect to the section 2, and whose free end is formed with an overturned lip 9, turned backwardly at an acute angle thereto.

The tongue 8 also has the underlying wings 60 10, 10' formed integrally with, and lying parallel to said tongue, and whose ends, adjacent the section 1 are free. These wings are additionally secured in place by means of a lug 11, cut from the material of the tongue 65 and bent backwardly over them.

In order to lock the sections together the free end of the tongue 8 is inserted through the slot 6 and the sections 1 and 2 are moved toward each other until the free end of the lip 9 clears the free edge of the flap 3 and the free ends of the wings 10 engage under the adjacent portion of the flap 3, as shown in Figures 1 and 2. In the form shown in Figure 70 3 the wings 10' are overturned one on each side of the tongue 8, and are secured in such position by the lugs 11' cut from the material of the tongue 8 and bent back over said respective wings 10'. When the sections 1 and 2, of the form shown in Figure 3 are 75 locked together the wings 10' will embrace the adjacent edge of the section 1, one on each side thereof. The wings 10', 10' protect the slot 6 against the entrance of a tool for releasing the lock.

When the lip 9 passes the free edge of the flap 3 it will spring open, or away from the tongue 8, and engage over said edge to prevent the withdrawal of the tongues 8 and the wings, referred to, will limit the inward 80 insertion of said tongue.

The interlocking parts of the lock, which secure together the parts of the container, to be secured together, are inaccessible and the container can only be opened by destroying the lock or tearing the same from the container.

95 While the device has been described as adapted for use in connection with boxes and envelopes, it is obvious that it may also be 100

used for other purposes, as with tying or securing cords or ribbons adapted to be passed around a container with the ends of the tying cord or ribbon fastened together by such locking device. The fastener may be used with containers of any character or material having parts which are to be secured together.

What I claim is:—

- 10 1. A lock of the character described including two sections adapted to be connected to the parts to be fastened together, one section having its opposite margins turned into substantially parallel relation with the main body of said sections, and having a transverse slot between the main body and one of said overturned portions, the other section having a tongue adapted to enter said slot, an overturned lip at the free end of the tongue adapted to engage over the adjacent one of said overturned margins, a wing carried by said tongue having a free end adapted to engage over the adjacent section, when said sections are interlocked together
- 15 20 25
- 20 and a lug turned over the wing to hold the same in engaging position.

2. A lock comprising two sections, means for securing the respective sections of the parts to be fastened together, one section having its opposing edges overturned into substantially parallel relation with the main body of said section forming longitudinal flaps and having a slot at the junction of one of said flaps with said main body portion, the other section having a tongue adapted to be inserted through said slot, the free end of the tongue being overturned forming a lip adapted to engage over the free margin of the adjacent flap, a wing carried by said tongue having a free end adapted to engage over the adjacent part of the adjoining section when said sections are locked together and a lug carried by the tongue and overlying said wing.

3. A lock composed of two sections, means for securing the respective sections of the parts to be fastened together, one section having one edge overturned forming an underlying flap and having a slot at the junction of said flap with the main body of said section, a tongue carried by the other section adapted to be inserted through said slot, spring means carried by the tongue adapted to engage the free margin of said flap, to interlock said sections together, wings carried by said tongue having free ends adapted to fold upon the tongue and embrace the other section when said sections are so locked together and means carried by the tongue and overlying said wings.

4. A lock of the character described comprising two sections, one having a catch and being formed with walls adapted to enclose said catch, said walls being formed with an opening through same, the other section hav-

ing a tongue adapted to enter said opening and comprising means for engaging the said catch and locking the sections together, the tongue having side wings adapted to overlap and surround the border of the opening thereby preventing the admission of a tool when the sections have been interlocked, a lug thrown out from the material of the tongue and turned over said wings.

In testimony whereof I have signed my name to this specification.

GONZALO ANCIRA.
